UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed December 6, 1922, Serial No. 605,149. Renewed September 26, 1927.

The present invention relates to telephone systems in general, but more particularly to automatic telephone systems; and the main object is the production of new and improved circuit arrangements particularly adapted for use in a small isolated automatic exchange, and which enable such an exchange to be manufactured very cheaply while retaining all the features necessary for modern high-class and dependable telephone service.

Such isolated exchanges are generally privately owned by an establishment that has use for an extensive intercommunicating system, such as, for example, a manufacturing establishment or a large department store.

One feature of the invention relates to improved circuit arrangements for a link circuit comprising a numerical forward selecting switch and a non-numerical line finder switch.

Another feature of the invention is an improved preselecting allotter which allot's the next link circuit for use when the allotted one is taken for use.

Still another feature relates to the improved line and cut-off relay combination.

A still further feature has to do with the improved common signalling equipment which furnishes the necessary tones and ringing current.

The other features which are concerned mainly with the circuit details will, together with the ones named above, be explained fully hereinafter, reference being had to the accompanying drawings which comprises Figs. 1-3, inclusive, and which show by means of the usual circuit diagrams a sufficient amount of the apparatus used in a system embodying the features of the invention to enable the invention to be understood and its utility appreciated.

Figure 1 of the drawings shows a calling subscriber's substation and line which terminates at the exchange in the banks of line finder switches and has associated with it the line circuit LC. Also, one of the finders is shown and the common finder allotter which allot's the idle finders for use.

Figure 2 shows a connector permanently associated with the finder F, Fig. 1 and having access to the line of substation A'

and also the other lines of the private automatic exchange.

Figure 3 shows the common signalling equipment which is used to supply ringing current, busy signalling current, and also dial tone to tell the calling subscriber when to begin to dial the number.

The automatic substations A and A' are similar to each other, and each has the usual talking, signalling, and switch controlling instrumentalities. The line circuit LC and LC', in which the lines of these substations terminate, are similar to each other, and each has the usual line and cut-off relays which, however, have novel circuit arrangements as will be pointed out hereinafter.

Each of the finders, such as the finder F, Fig. 1, and the operating mechanisms O and O' of the finder allotter FA is of the well-known rotary type of switch, of which the wipers move in a forward direction only and have no normal position.

The connector C, Fig. 2, is of the well-known vertical and rotary type and, accordingly, its bank contacts are arranged in horizontal rows or levels according to the usual and well-known practice.

In order to facilitate the detailed description of the operation of the apparatus shown, it will be assumed that the subscriber at substation A desires to converse with the subscriber at substation A'.

When the receiver is removed at substation A, line relay 14 of the line circuit LC energizes over the line conductors 11 and 12 by means of its upper winding, which is connected to conductor 12 through armature 15 of cut-off relay 13 and its resting contact, conductor 11 being grounded at this time through the resting contact of armature 17 of cut-off relay 13 and said armature, and the common conductor 25. Upon energizing, line relay 14 disconnects ground from test contact 22 and its multiples in the banks of the finders at armatures 18 and 19; connects conductor 27 with private normal conductor 28 and cut-off relay 13 at armature 18; places ground on the signal start conductor 24 at armature 19; and at armature 20 places ground through armature 16 and its resting contact on the finder start conductor 26.

Assuming the operating mechanism O of

the finder allotter FA to be resting with the wipers 68 and 69 on the bank contacts 72 and 73 of the finder F, line relay 37 of the finder F energizes over the following circuit: from ground by way of the common start conductor 26, resting contact of armature 85 and said armature, spring 66 of the push button P and its resting contact, wiper 69, bank contact 73, and line relay 37 of the finder F to battery. Upon energizing, line relay 37 closes a circuit for switching relay 36 and stepping magnet 35 in series at armature 47, and at armature 46 connects test wiper 39 of the finder F to the junction of switching relay 36 and stepping magnet 35. Assuming the wipers 38-40, inclusive, of the finder to be standing on the bank contacts 21-23, inclusive, of the calling line, the latter operation of line relay 37 does not have any effect at this time and switching relay 36 energizes immediately. Assuming, however, that the wipers of the finder are standing on the bank contacts of a non-calling or a busy line, switching relay 36 is short-circuited by the ground potential found by test wiper 39, and stepping magnet 35 is operated from this same ground potential, and the wipers of the finder are advanced step by step by the buzzer-like action of stepping magnet 35 in search of the calling line. When the terminals of the calling line are reached, test wiper 39 encounters an ungrounded contact, and switching relay 36, being no longer short-circuited, energizes in series with stepping magnet 35. Stepping magnet 35, however, does not energize at this time on account of the high resistance of switching relay 36. Upon energizing, switching relay 36 connects the line conductors of the calling line with the corresponding conductors 48 and 53 of the connector C at armatures 41 and 45; closes a point in the circuit of chain relay 83 at armature 42; prepares a locking circuit for itself and grounds conductor 51 at armature 44; and at armature 43 disconnects test wiper 39 from the junction of its own winding and stepping magnet 35, and connects it to ground, thereby placing a busy potential on private normal conductor 28 of the calling line, and closing a circuit for cut-off relay 13 in series with the lower winding of line relay 14. Upon energizing, cut-off relay 13 disconnects ground from start conductor 26 at armature 16, thereby opening the circuit of line relay 37 of the finder F. Line relay 37, however, being slow-acting, does not deenergize immediately. As a further result of the energization of cut-off relay 13, it disconnects the calling bridge at armatures 15 and 17. Line relay 14, however, does not deenergize at this time but is held energized in series with cut-off relay 13 by its own lower winding.

As a result of conductor 51 being

grounded upon the energization of relay 36 of the finder as above explained, stepping magnet 63 energizes over the following circuit: from ground by way of the working contact of armature 47 and said armature, working contact of armature 44 and said armature, conductor 51, resting contact of armature 130 and said armature, conductor 52, bank contact 72, wiper 68, resting contact of spring 65 and said spring, armature 86 and its resting contact, and stepping magnet 63 to battery. Stepping magnet 63 now advances wipers 68 and 69 from engagement with bank contacts 72 and 73, and continues to advance them by its buzzer-like action until wiper 68 comes into engagement with an ungrounded contact which denotes that an idle finder connector link is reached. The line relay of the allotted finder is not operated, however, until another call is made for the reason that ground is removed from the start conductor 26, prior to the new finder being allotted, by cut-off relay 13 as explained above. During the time in which the wipers 68 and 69 are being rotated in search of an idle finder connector link, relay 61 is held energized in multiple with stepping magnet 63 by its upper winding, and maintains the start conductor open at armature 85 so as to prevent the energization of the line relays of the busy finders passed over by wipers 68 and 69 in case start conductor 26 again becomes grounded, due to another call being originated, before the next finder is allotted.

In the connector C, line relay 102 energizes over the calling line in response to the previously described operation of switching relay 36 of the finder F, the lower winding of relay 102 being grounded through the common dial tone conductor 172. Upon energizing, relay 102 closes a circuit for release relay 103 at armature 120. Release relay 103, upon energizing, opens a point in the circuit of common signal 171 at armature 124 and prepares a circuit for vertical magnet 112; places ground on locking conductor 175 at armature 123; and at armature 122 grounds holding conductor 52, thereby establishing a holding circuit for switching relay 36 of the finder F by way of armature 44 and its working contact before the slow acting line relay 37 has had time to deenergize.

The calling subscriber now hears the dial tone, which is placed on the common conductor 172 by the signal equipment shown in Fig. 3 in a manner to be explained herein-after, and knows that he may now call the desired number.

In response to the calling of the first digit in the desired number, line relay 102 is deenergized a corresponding number of times in response to the interruptions of its circuit at the calling substation. Upon each of the

resulting deenergizations of line relay 102, an impulse of current is sent to vertical magnet 112, the first impulse of current being transmitted over the following circuit: 5 from ground by way of armature 120 and its resting contact, armature 124 and its working contact, contact of off-normal spring 127 and said spring, relay 104, and vertical magnet 112 to battery. By the operation of vertical magnet 112, the wipers 148-150, inclusive, of the connector are raised opposite the level of contacts in which the desired line terminates. Relay 104 is energized in series with vertical magnet 112 and, being slow-acting, retains its armature attracted throughout the vertical movement. The energization of relay 104 serves, at armature 126, to maintain the circuit of relay 104 and vertical magnet 112 intact after the off-normal springs have shifted, as they do upon the first vertical step. As a further result of the energization of relay 104, it closes a circuit for relay 101 at armature 125. Upon energizing, relay 101 closes a locking circuit for itself at armature 115; opens the point in the circuit of the common signal 171 and prepares a circuit for release magnet 111 at armature 116; places direct ground on the lower winding of line relay 102 at armature 119 and disconnects the dial tone conductor 172 therefrom; connects up the lower talking condenser to conductor 53 at armature 117, the lower talking condenser being normally disconnected to prevent a normal flow of dial tone through the lower talking condenser and through the lower winding of impedance 105 to battery by way of the lower winding of ring-cut-off relay 109.

At the end of the vertical movement, series relay 104 deenergizes; opens the initial circuit of relay 101 at armature 125, leaving relay 101 energized over its locking circuit which includes armature 115; and at armature 126 opens the point in its own circuit and that of the vertical magnet 112 and extends the operating circuit to rotary magnet 113.

When the calling subscriber operates his calling device in accordance with the second digit of the desired number, the corresponding deenergizations of line relay 102 result in a corresponding number of impulses being transmitted to rotary magnet 113. The circuit over which the first of these impulses is transmitted, is as follows: from ground by way of armature 120 and its resting contact, armature 124 and its working contact, normally open contacts controlled by off-normal spring 127, armature 126 and its resting contact, armature 137 and its resting contact, armature 146 and its resting contact, and rotary magnet 113 to battery. By the operation of rotary magnet 113, the wipers 148-150, inclusive, are rotated into engagement with the bank contacts 151-153, inclusive, of the called line. Slow acting relay 107 is energized in multiple with rotary magnet 113 and retains its armature attracted throughout the rotary movement. Upon energizing, relay 107 disconnects test wiper 149 from the lower winding of switching relay 110, and connects it to busy relay 108 at armature 134, and at armature 135 places a shunt around armature 137 and its resting contact, so as to prevent any energization of busy relay 108, which is likely to occur during the rotary movement while test wiper 149 is passing over grounded test contacts, from opening the circuit of relay 107 and rotary magnet 113.

It will be assumed first that the called line is busy, in which case test conductor 152 is grounded, and when test wiper 149 arrives on test contact 152, busy relay 108 energizes through the normally closed contacts controlled by armature 144, and armature 134 and its working contact; prepares the busy signalling circuit at armature 138; opens a point in the circuit of relay 107 and rotary magnet 113 at armature 137; and at armature 136 disconnects the locking conductor 175 from the lower winding of relay 110 and prepares a locking circuit for itself.

Under these conditions, when slow-acting relay 107 deenergizes at the end of the rotary movement, it disconnects itself and rotary magnet 113 from the operating circuit at armature 135; completes a locking circuit for busy relay 108 at the normally closed contacts controlled by armature 134; and at the normally closed contacts controlled by armature 133, places the busy tone which is on the busy signalling conductor 174, on the lower heavy talking conductor 53 by way of the lower talking condenser and armature 117 and its working contact. By this operation, a busy signal is transmitted back to the calling subscriber to inform him that he cannot, for the time being, obtain the desired connection and, when the calling subscriber replaces his receiver, the partially established connection is released in the usual manner.

It will be assumed now that the line of substation A' is idle when called, as hereinbefore described. That being the case, busy relay 108 is not energized when the wipers of the connector come to rest on the terminals of the called line and relay 107, upon deenergizing, completes a circuit for the lower winding of switching relay 110 in series with cut-off relay 154 and the lower winding of line relay 155 of the line circuit LC' as follows: from ground by way of locking conductor 175, armature 136 of busy relay 108 and its resting contact, lower winding of relay 110, resting contact of armature 134 and said armature, normally closed contacts controlled by armature 144, test wiper 149, test contact 152, cut-off relay 154 and the lower winding of line relay 155.

1154 and the lower winding of relay 155 to battery. Cut-off relay 154, upon energizing, clears the called line of its bridge at its upper and lower armatures. The energization of line relay 155, however, is merely incidental at this time and does not perform any particular function.

In the connector C, switching relay 110, upon energizing, closes a locking circuit for 10 itself first at its lightly adjusted armature 145, and then disconnects rotary magnet 113 at armature 146 so as to prevent any further rotation of the wipers in case the calling subscriber again turns his calling 15 device; disconnects ground from the upper terminal of relay 106 and places direct ground on test wiper 149 at armature 144; disconnects armature 134 of relay 107 from test wiper 149 at the normally closed contacts controlled by armature 144; and at 20 armature 143 and 147 connects up the line wipers 148 and 150, whereupon ringing current is intermittently projected out over the lower talking conductor to the called 25 station from the common ringing conductor 173, and returns by way of the upper talking conductor to battery by way of the upper winding of ring-cut-off relay 109.

When the called subscriber responds to 30 the ringing of his bell by removing his receiver, ring-cut-off relay 109 energizes over the called line from ground on common ringing conductor 173, and closes a locking circuit for itself at its lightly adjusted armature 141, and then places a shunt around the resting contact of armature 130 and said armature at armature 140 for a reason which will be pointed out fully hereinafter; and at armatures 139 and 142 disconnects the 35 conductors of the called line from the source of ringing current and its own upper winding, and extends them to the windings of battery feed impedance 105 by way of armature 133 and its resting contact, and the 40 working contact of armature 121 and said armature. The called subscriber now receives talking battery through the upper winding of impedance 105 and the return circuit to ground is afforded through the 45 lower winding of impedance 105, armature 132 and its resting contact, and the working contact of armature 141 and said armature to the grounded locking conductor 175. The 50 reasons for leaving the lower winding of impedance 105 ungrounded until ring-cut-off relay 109 energizes is to give the calling subscriber an audible ringing signal due to the ringing current returning through the upper winding of ring-cut-off relay 109, and 55 60 inducing a tone by transformer action in the lower winding of relay 109 which is transmitted to the lower talking conductor through the lower winding of impedance 105.

The calling and called subscribers may

now converse with each other as desired and when the conversation is finished, they both replace their receivers.

When the receiver is replaced at the called substation A', no particular result is accomplished in the connector C except that current merely stops flowing through the talking-battery-feed impedance 105.

When the receiver is replaced at substation A, line relay 102 of the connector C deenergizes and opens the circuit of slow-acting release relay 103 at armature 120, at the same time closing a circuit for slow-acting relay 107. Relay 107 energizes at this time, but does not perform any particular function.

When slow-acting relay 103 lets go, it removes ground from guarding conductor 52 and holding conductor 51 at armature 122, whereupon the finder connector link is rendered selectable to the finder allotter FA again and switching relay 36 of the finder F deenergizes; disconnects the conductors of the line of substation A from the line conductors of the connector C at armatures 41 and 42; and removes ground from test wiper 39 at armature 43, allowing relays 13 and 14 of the line circuit LC to deenergize. As a further result of the deenergization of release relay 103, it removes ground from locking conductor 175 at armature 123, thereby opening the circuit of relays 101, 109, and 110. Relay 110 deenergizes promptly. Relay 101 and relay 109, however, being slow-acting, retain their armatures attracted for an interval.

As a still further result of the deenergization of relay 103, a circuit for release magnet 111 is closed as follows: from ground by way of armature 120 and its resting contact, armature 124 and its resting contact, armature 116 and its working contact, and release magnet 111 to battery. Upon the energization of release magnet 111, the shaft and wipers of the connector C are restored to normal position. When the normal position is reached, a point in the circuit of the common alarm signal 171 is opened at off-normal contacts 128. Shortly after its circuit is opened, relay 109 deenergizes and restores its armatures to normal. Relay 101 deenergizes after an interval, but in case the connector is in working order mechanically and has been restored to normal by release magnet 111, no particular result is accomplished. Assuming, however, that the switch shaft was not restored to normal, the off-normal contacts 128 are closed, and the common alarm signal 171 is sounded when armature 116 opens the circuit of release magnet 111 and comes into engagement with its resting contact. An attendant 115 may respond to the alarm and take the necessary steps to clear up the trouble.

The function of the jack J will now be explained. It sometimes becomes necessary to temporarily remove the finder connector 120 125 130

link from service and when such an occasion arises, a flat piece of conducting material about the size of a five-cent piece is inserted between the springs of the jack J, thereby closing a circuit for the lower winding of relay 106. Relay 106, upon energizing under these conditions, separates conductors 51 and 52 at armature 130, and places ground on conductor 52 so as to render the finder connector link non-selectable to the finder allotter FA, and at armature 129 places a shunt around the chain contacts 42 of the finder F so as to impose the same condition on the chain circuit as is there when the finder connector link is in actual use.

It may occur occasionally that all the finder connector links become busy, and that a subscriber attempts to originate a call at this time and is unsuccessful because no finder connector link is available. Assuming that all the finder connectors become busy, all the contact points, such as armature 42 of switching relay 36 and its working contact, in the circuit of chain relay 83 are closed and chain relay 83 energizes; disconnects stepping magnets 63 and 64 at armatures 86 and 87 so as to prevent useless hunting operation at this time; and at armature 89 closes a circuit for relay 62. Relay 62 thereupon energizes and connects the all trunks busy tone conductor 54 with the common conductor 25 and disconnects ground therefrom, so as to give a distinctive tone to any subscriber who happens to take off his receiver at this time. It may be stated that this tone is taken from the ringing current lead through a small condenser as may be seen in Fig. 3. This small condenser cuts down the loudness of the tone considerably, but allows a tone to pass which is very much louder than either the ordinary busy signalling tone or the dial tone ordinarily received soon after the subscriber removes his receiver. For this reason, the subscriber, upon hearing the all trunks busy tone, is able to distinguish that tone by its loudness, and is informed thereby that all the connecting links are busy. The subscriber may now replace his receiver and wait a while for a trunk to become idle, or he may leave his receiver off the hook and wait until his line is found by a finder.

Assuming that all the finder connector links are busy, and that several subscribers have their receivers off waiting for dial tone and are listening to the tone placed on by relay 62 of the finder allotter FA, all the subscribers who are waiting for the dial tone note the cessation of the all trunks busy tone when a trunk becomes idle and relay 62 de-energizes due to the deenergization of chain relay 83. However, all the waiting subscribers, except the one whose line is found by the finder which becomes idle, hear the

all trunks busy tone again when the switching relay of the finder corresponding to switching relay 36 of the finder F energizes and closes the chain again upon finding one of the calling lines. This process, of course, is repeated until all the waiting lines have been taken care of, and the intermittent interruption of the all trunks busy tone may be exceedingly puzzling to the subscribers who hear it several times before their respective lines are found or it may even be the source of considerable annoyance. In order to furnish a means to prevent the all trunks busy tone from being interrupted while two or more subscribers are waiting at such a time, the locking push-button P' has been provided and may be operated, when desired, to connect the working contact of armature 84 of relay 62 to the common start conductor 26. When this is done, relay 62 becomes locked up independent of chain relay 83 through armature 84 and its working contact and the normally open contacts of the push-button P' to start conductor 26 and, consequently, does not deenergize again until the lines of all the waiting subscribers have been found, or until all the subscribers have hung up their receivers and thereby removed ground from the start conductor, in which case relay 62 deenergizes in case chain relay 83 has fallen back.

The working contact of armature 84 is not permanently connected with start conductor 26 for the reason that it may at some time be desirable to have relay 62 fall back each time the chain circuit is opened, so that an observer who is making a call may have some fair idea as to the way in which the traffic is being handled, as is determined by the frequency at which the all trunks busy tone is interrupted.

Since, the finder allotter is common to several finders, it is extremely important to guard against any mechanical trouble that may arise in the finder allotter from time to time, especially since the finder allotter must operate each time a call is made and, for that reason, receives considerable use. In order to guard against the service from being tied up owing to a mechanical failure in the finder allotter, a second operating mechanism, which is shown inside the dotted rectangle denoted by the reference character O', has been provided and, when it is desired to do so, the push-button P may be operated with the result that the operating mechanism shown in the dotted rectangle indicated by the reference character O is disconnected at spring 65 and the substitute operating mechanism is connected up at spring 67. Also, the start conductor 26 is shifted from wiper 69 of the first operating mechanism to wiper 70 of the second operating mechanism at spring 66. It may be pointed out that relay

61 is operative when the second operating mechanism is used owing to the fact that it has a second winding in multiple with the second operating magnet which allows it to 5 operate just as though the first operating mechanism were in use.

The operation of the common signalling equipment shown in Fig. 3 will now be described. Of this equipment, the ringing interrupter relays 201-205, inclusive, and the 10 associated marginal relay 206 will be considered first. The ringing interrupter relays 201-205, inclusive, are provided for the purpose of interrupting the supply of ringing 15 current so as to project ringing current out on a called line intermittently, and also to distribute the ringing periods of the five ringing leads so as to lower the maximum demand for ringing current in order to allow 20 a source of ringing current of a smaller capacity to be used than would be necessary were the ringing current supplied to all the ringing leads simultaneously.

For the purpose of the following description, it will be assumed that a call is made. 25 This results in the signal start conductor 24 being grounded as hereinbefore described. When this occurs, the first interrupter relay 201 energizes through the resting contact of armature 242 and said armature, and in series with the low wound marginal relay 206. Marginal relay 206, however, 30 does not energize in series with one of the interrupter relays alone, and, consequently, remains inert for the time being. In order 35 to time the operation of the interrupter relays properly, they are made slow to de-energize by the well-known expedient of placing a copper collar around the core, and are made slow to energize by placing the 40 copper collar around the armature end of the core rather than the opposite end. This means of making a relay slow to pull up is, of course, well-known to those skilled in 45 the art, and is taken advantage of in this case merely to slow up the cycle of operation still more. In the drawings those relays which are slow to pull up are indicated by solid black portions at the upper ends of 50 their cores in order to distinguish them from the ordinary slow to release relays which have the lower ends of their cores cross hatched. When relay 201 energizes, it disconnects the first ringing current lead from 55 ground and connects it with the secondary winding of the ringing current transformer T. As a further result of the energization of relay 201, it opens a point in the circuit of relay 203 at armature 226, and at armature 227 closes a circuit for relay 202 by 60 way of the resting contact of armature 234 and said armature. When this occurs, the marginally adjusted relay 206 energizes and opens the circuit of relay 201 at armature

242. Relays 201, however, remains energized 65 for an interval, owing to the fact that it is slow-acting and maintains the circuit of relay 202 closed until the latter relay energizes. Upon energizing, relay 202 shifts the 70 ringing lead controlled thereby to the second- 75 ary winding of the ringing current trans- former at armature 222; opens a point in the circuit of relay 204 at armature 228; and at armature 229 prepares a circuit for relay 203.

When relay 201 deenergizes, it connects the ringing lead which it controls back to ground again at armature 221; opens the circuit of the slow-acting relay 202 at armature 227; and at armature 226 completes the 80 circuit of relay 203. Relay 203, upon energizing, prepares a circuit for relay 204 at armature 231; opens a point in the circuit of relay 205 at armature 230; and at armature 223 shifts its ringing lead in the usual 85 manner.

When relay 202 deenergizes, it, among other things which are apparent, completes the circuit of relay 204 at armature 228, and relay 204, upon energizing, prepares a circuit 90 for relay 205 at armature 233; opens a point in the circuit of relay 201 at armature 232; and at armature 224 shifts its ringing lead to the secondary winding of the ringing current transformer.

When relay 203 deenergizes, it completes the circuit of relay 205 at armature 230, and relay 205, upon energizing, closes a point in the circuit of relay 201 at armature 235; opens a point in the circuit of relay 202 at 100 armature 234; and at armature 225 shifts ringing lead 173 from ground to the secondary winding of the ringing current transformer.

When relay 204 deenergizes, it opens the 105 circuit of relay 205 at armature 233 and completes the circuit of relay 201 at armature 232. When this occurs, relay 201 energizes again with the results hereinbefore described.

When relay 205 deenergizes, relay 202 energizes again as before described.

This cycle of operation is repeated over and over as long as conductor 24 remains grounded, and the ringing leads are connected to the secondary winding of the ringing current transformer one by one in order. There is, however, an overlapping or a time interval during which two ringing leads are connected to the secondary winding of the 120 ringing current transformer. This, however, does not cause any trouble for the reason that the ringing current transformer T and the associated vibrator are designed to supply ringing current to two leads simultaneously.

The operation of the vibrator magnet 211 and pendulum 238 will now be taken up.

As a further result of the ground potential being placed on conductor 24, a circuit is closed for the high-wound slow-to-energize relay 207. This relay, however, does not 5 become sufficiently energized for a moment to attract its armature. As a further result of the ground potential being placed on conductor 24, a circuit is closed for magnet 211 in series with the lower winding of impedance 10 208, and in series with both windings of the choke coil impedance 212. Upon energizing, magnet 211 attracts its armature and the pendulum 238 swings to the left and short circuits magnet 211, whereupon 15 the magnet 211 deenergizes and the pendulum swings in the opposite direction. After one or two swings of the pendulum 238, the cycle of operation becomes steady, and the time required for one complete swing is determined 20 by the weight attached to the pendulum.

After a time which is sufficient to allow the pendulum to pick up speed and vibrate at its full amplitude, the slow to energize 25 relay 207 energizes and places ground on the mid-point of the primary winding of the ringing current transformer T by way of the left-hand winding of the choke coil impedance 212. After this is done, each backward 30 swing of the pendulum results in a circuit being closed for the upper section of the primary winding of the transformer T, and each forward swing of the pendulum results in a circuit being closed for the lower section of the primary winding and, consequently, an alternating current is driven 35 through the secondary winding of the transformer T. The choke coil 212 and the condenser 243 are used to smooth out the flow 40 of battery current so as to prevent the battery from being "noisy", and causing unpleasant noises while the subscribers are conversing.

Since, the lower winding of impedance 45 208 is in series with the winding of vibrator magnet 211, the current in the former fluctuates owing to the intermittent short-circuiting of the latter by the vibrating pendulum 238. This fluctuating current in the 50 lower winding of impedance 208 causes a corresponding fluctuating electro-motive force to be applied to the dial tone conductor 172 and through the upper winding of said impedance 208. The small condenser 209 which is connected between the 55 right-hand terminals of the upper and lower windings, respectively, allows some of the fluctuations in the E. M. F. applied to the terminals of the lower winding to pass 60 directly across to conductor 172 so as to strengthen the dial tone without adding more turns to the upper winding of impedance 208 and, consequently, without increasing the resistance of impedance 208 to a

point at which the operation of the line relays of the various associated connectors might be affected.

As a still further result of the ground potential being placed on conductor 24, a circuit is closed for the busy interrupter 70 relay 214 by the way of armature 243' of relay 212' and its resting contact. Upon energizing, relay 214 closes a circuit for relay 212' at armature 240, and relay 212', upon energizing, opens the circuit of relay 214 at armature 243'. After an interval, relay 214 deenergizes and opens the circuit of relay 212' and relay 212', upon deenergizing, again closes the circuit of relay 214. This cycle of operation is repeated over and over as long as conductor 24 remains grounded. It will be noted that each time relay 212' energizes, it closes a circuit for the lower winding of relay 213. Relay 213, 80 upon energizing, closes a circuit for its upper winding at armature 239, which upper winding is wound in opposition to the lower winding. Consequently, relay 213 immediately deenergizes again and, as a result, buzzes at a high rate of speed as long as relay 212' is energized and start conductor 24 grounded. Obviously, since relay 212' deenergizes at intervals, as pointed out above, the buzzing of relay 213 is interrupted at intervals, of which the time depends upon the adjustments of the relays 212' and 214. The operation of relay 213 causes an intermittent buzzing tone to be placed on the busy signalling conductor 174 through the condenser 244. 100

When ground is removed from start conductor 24, it is obvious that the ringing interrupter relays, the vibrator, and the busy signalling relays stop operating.

In a private automatic exchange, special 105 services are commonly provided for such as, for example, a common call system, a conference call system, and others of a somewhat similar nature. The connector C, Fig. 2, is arranged to disconnect battery and ground from the back bridge on the tenth level and to repeat impulses in order to provide for such services. In order to give an understanding of the functions of the connector C when raised to the tenth level and brought into engagement with one of the 110 set of contacts in that level, reference may be had to the co-pending application of Jones, Serial No. 443,654, filed February 9, 1921, which shows a private automatic exchange connector having access on a certain set of contacts to a conference call connector. 115

In order to explain the operation of the connector C when used as a repeater, it will be assumed that a subscriber has initiated a call; is using the connector C; and has operated his calling device in accordance with the 120 125

- first digit 0 in the desired number, which is the digit dialled when any special service is desired. The various relay operations which take place when the first digit in a number is called, occur at this time as described hereinbefore, and vertical magnet 112 raises the associated wipers opposite the tenth level of bank contacts, whereupon the tenth level springs are operated and contact 10 114 is closed, thereby closing the following circuit for ring-cut-off relay 109: from ground by way of armature 144 of switching relay 110 and its resting contact, contacts 114 of the tenth level springs, and the 15 upper winding of ring-cut-off relay 109 to battery. Upon energizing, ring-cut-off relay places the circuits in such a condition that no ringing current will be projected when the wipers are moved into engagement with the desired set of contacts, and also places a shunt around armature 130 of relay 106 and its resting contact to prevent the ground potential from being removed from holding conductor 51 upon the energization of relay 106, which occurs subsequently.

- Upon the next operation of the calling subscriber's calling device, the wipers 148-150, inclusive, are brought into engagement 20 with the desired set of bank contacts and the usual busy test is made. Assuming the trunk terminating in these contacts to be idle, switching relay 110 energizes through test wiper 149 from battery on the test conductor of the trunk as shown in the Jones application above referred to, and connects up the line wipers and performs the other operations hereinbefore described. When armature 144 breaks away from its resting 25 contact, the shunt is removed from the upper winding of relay 106, whereupon relay 106 energizes in series with the upper winding of ring-cut-off relay 109, and at armatures 131 and 132 disconnects battery and 30 ground from the windings of the battery feed impedance 105 and connects the windings together, thereby closing a holding bridge across the line conductors of the seized trunk, whereupon the line and release 35 relays of the seized trunk energize in the usual manner.

- Upon each of the subsequent operations of the calling subscriber's calling device, an interruption is produced in the circuit of 40 the line relay of the seized trunk at armature 121 of line relay 102, thereby operating the seized switch in the usual manner. Also, the usual impulses of current are sent over the operating circuit to slow-acting relay 107 with the result that this relay is maintained energized during each series of impulses which are repeated, and at armature 133 disconnects the upper line wiper 45 from the upper talking condenser and closes the bridge across the line wipers by a more

direct path which is exclusive of the windings of impedance 105. This is the usual expedient made use of in order to obtain a better repeating circuit.

When the calling subscriber replaces his 70 receiver, the connector C is released in the usual manner, and the seized switch is released in response to the opening of the bridge across the line wipers of the connector C at armature 121 of line relay 102. 75

What is claimed is:

1. In a telephone system, a line, a line circuit therefor comprising a line relay connected thereto and a cut-off relay for disconnecting said line relay from said line, 80 line finders for finding said line when a call is made thereover, connectors for connecting with said line when it is called, said line relay energizing alone when a call is made over said line, and said line and cut-off relay energizing in series whenever said line is found by a finder or is connected with by a connector.

2. In a finder system, a plurality of finders an allotter for allotting an idle one for use 85 when the allotted one is taken for use, said allotter comprising two operating mechanisms and a group of relays common to both said operating mechanisms, and a manually operable device for disconnecting 90 either operating mechanism from the associated relays and substituting the other operating mechanism.

3. In a telephone system, a plurality of lines, a plurality of finders for finding the 100 calling ones of said lines, a relay operated when all of said finders are busy, means controlled by said relay for placing a tone on all unfound lines, and means for maintaining said relay in said operated position independent of the busy or idle condition of 105 said finders when there is an unfound calling line.

4. An automatic switch having wipers, said wipers having a normal position, means 110 for moving said wipers from their normal position to effect a connection, a release magnet for restoring said wipers to their normal position, a slow-acting release relay energized under the control of a calling line, 115 a second slow-acting relay maintained energized by said release relay, means for opening the circuit of said slow-acting release relay when a call is terminated, circuit connections such that said release relay, on falling back, opens the circuit of said second slow-acting relay and closes the circuit of 120 said release magnet, circuit connections such that said second slow-acting relay, on falling back, opens the circuit of said release magnet and also closes an alarm circuit in case 125 said wipers have not been returned to normal.

5. In a telephone system, a line, a finder switch, line and cut-off relays for said line,

- a circuit for said line relay excluding the cut-off relay completed when a call is initiated, a circuit for starting said finder completed responsive to the energization of said line relay, and a circuit including both relays completed by said finder when the line is found. 5
6. In a telephone system, a line, a finder switch, a line relay normally connected to said line, a cut-off relay for disconnecting said line relay, circuits controlled by said line relay for starting said finder and for rendering the said line selectable to said finder, said starting circuit being maintained closed until the said line is found, means for energizing said cut off relay when the line is found and means for maintaining the line relay energized after it is disconnected from the line. 10
11. In a finder system, an allotter comprising two separate switches, a finder start circuit, means in both switches for extending said circuit to idle finders, an allotter control circuit, and means for associating said control circuit with either one of said switches independent of the other. 15
12. In a telephone system, a group of lines, a group of finder connector link circuits for extending said lines when calling, a relay and means controlled thereby for giving a calling subscriber a busy signal in case all said link circuits are busy when the call is initiated, a circuit for said relay including serially related contacts in each finder, and contacts in each connector for shunting the series contacts in the associated finder. 20
13. In a telephone system, a group of lines, a group of finder connector link circuits for extending said lines when calling, a relay and means controlled thereby for giving a calling subscriber a busy signal in case all said link circuits are busy when the call is initiated, a circuit for said relay including serially related contacts in each finder, contacts in each connector for shunting the series contacts in the associated finder, and means operated by an attendant for controlling the closure of said shunt contacts. 25
14. In a telephone system, a line, a link circuit including a finder and a connector for extending said line, a slow acting relay in said connector controlling the release of said finder, a second slow acting relay in said connector, and a release magnet in said connector controlled jointly by said relays. 30
15. In a telephone system, finders for extending calling lines, means controlled over a circuit including serially related contacts in each finder for signalling a calling line in case all said finders are busy, and means manually controlled at will for shunting said contacts. 35
16. In a telephone system, finders for extending calling lines, means controlled over a circuit including serially related pairs of contacts in each finder for signalling a calling line in case all said finders are busy, and means manually controlled at will for shunting said pairs of contacts separately. 40
17. In a telephone system, a switching device terminating a trunk line, means for seizing said trunk line and for operating said device, a first relay operated when said trunk line is seized, a second relay initially operated when said switch is operated, the operation of said second relay being thereafter under the control of said first relay, and a release circuit for said device jointly controlled by both said relays. 45
18. In a telephone system, link circuits for extending calling lines, a signalling device initially rendered effective responsive to all said link circuits becoming busy, and means for maintaining said device effective while any calling line is waiting to be extended. 50
19. In a telephone system, link circuits for extending calling lines, a signalling device, means responsive to all said link circuits becoming busy for initially rendering said signalling device effective, and means jointly controlled by said first means and by calling lines waiting to be extended for maintaining said device effective. 55
20. In a telephone system, an automatic switch, subscribers' lines terminating in the banks of said switch, means for operating said switch to connect with a subscriber's line, means including a switching relay for signalling said subscriber, a ring cut-off relay and a third relay for placing a bridge across the talking conductors of said switch, means responsive to a partial operation of said switch for closing a circuit for said ring cut-off relay in series with said third relay, said ring cut-off relay operating thereafter, and means for delaying the operation of said third relay until said switching relay is operated. 60
21. In a telephone system, a group of lines, a group of finder connector link circuits for extending said lines when calling, a relay and means controlled thereby for giving a calling subscriber a busy signal in case all said link circuits are busy when a call is initiated, a circuit for said relay including serially related contacts in each finder, and means outside of each finder for shunting the series contacts therein to mark that finder in use. 65
22. In a telephone system, a plurality of subscribers lines, an automatic switch for connecting any two of said lines together, said switch having a normal position, a release magnet in said switch for returning the switch to its normal position for disconnecting said lines, a relay, and an energizing circuit for said magnet controlled by said relay, said relay having means for closing a point in said circuit and for opening it shortly after said magnet energizes for pre- 70

venting said magnet from burning up should the switch fail to return to its normal position.

19. In a telephone system, an automatic switch, a release magnet therefor, a circuit for said magnet, a relay for completing said release magnet circuit to energize said relay, a second relay having means for preparing

said circuit before the first relay completes said circuit, said second relay also opening 10 said circuit a predetermined interval after the said magnet is energized.

In witness whereof, I hereunto subscribe my name this 2d day of December, A. D., 1922.

CLARENCE E. LOMAX.
